UNITED STATES PATENT OFFICE.

DARWIN H. COOK AND ERVON J. WILSON, OF MINOT, NORTH DAKOTA.

CLUTCH FOR BLOWER-FANS AND THE LIKE.

1,052,046.

Specification of Letters Patent. Patented Feb. 4, 1913.

Application filed September 26, 1912. Serial No. 722,548.

To all whom it may concern:

Be it known that we, DARWIN H. COOK and ERVON J. WILSON, citizens of the United States, residing at Minot, North Dakota, have invented certain new and useful Improvements in Clutches for Blower-Fans and the Like, of which the following is a specification.

Our invention relates to clutch mechanism and is particularly designed by us for use in connection with a fan or blower for grain separating machinery or threshers.

One object of the invention is to permit the fan to run ahead of the shaft should the shaft for any reason be irregular in its revolution or become clogged in its action.

In the accompanying drawings Figure 1 is a face view of the blower or fan member with the cap or top plate removed, and Fig. 2 is a sectional view substantially on line 2—2 of Fig. 1.

In these drawings the blower or fan 1 is provided with a hub or rim 2, within which is seated a plate or disk 3 and through this disk the shaft 4 passes, the said shaft having a cross arm or head 5 with rollers 6 seated in the recesses 7 at the ends of the said cross arm. This arm is keyed to the drive shaft 4. The disk 3 carries a pair of friction shoes 8, each one of these shoes is pivotally mounted as at 9, and they are both adapted to bear at their portions 10 against the inside of the rim or hub 2 of the blower. These portions 10 on their inner sides have inclines 11 upon which the balls or rollers 6 are adapted to work. The friction shoes also have extensions 12 and these lie with their free ends adjacent the opposite ends of the cross arm or cross head 5. Supposing the shaft to be turning in the direction of the arrow X, the rollers 6 will tend to roll up to the high points of the inclines and therefore the friction shoes will be moved radially outward at their portions 10, turning on their pivots for this purpose, and the wedging action of the rollers on the inclines will therefore cause the shoes to grip the interior of the rim or hub 2, and the said rim together with the blower fan or other member to be driven will be carried around in unison with the

shaft and cross arm 5. Should it transpire however, that the rotation of the shaft is irregular, for instance through the clogging of its driving mechanism, the blower will be free to run ahead of the shaft to compensate for this irregularity in the shaft's rotation, this being particularly desirable in a fan for a thresher so that the blowing operation will be kept as uniform as possible. Supposing, therefore, the shaft suddenly slows down, this will be the equivalent relatively to a movement of the cross head or arm 5 in the arrow direction Y in respect to the hub or rim 2 of the fan. This action will not only cause the rollers to move down the inclines and thus relieve pressure on the shoes but it will bring the ends of the cross arm 5 against the extensions 12 of the pivotally mounted shoes so that said shoes will be moved inwardly away from the rim or hub at their gripping portions 10 and therefore the hub together with the fan will be free to rotate ahead of the shaft and its cross arm. By this construction the releasing operation is rendered quick and certain and the shoes take the wear off the rollers, the said shoes being readily replaceable. These shoes have a long frictional bearing against the interior of the hub or rim and distribute the wear over a considerable surface.

We claim as our invention:

In combination with the member to be driven, a cross arm or head having anti-friction members at its ends, shoes having inclines upon which said anti-friction members work, said shoes being adapted to frictionally engage a portion of the member to be driven, a carrier or support to which the said shoes are pivotally mounted, said shoes having extensions reaching to a point adjacent the ends of the arms, substantially as described.

In testimony whereof we affix our signatures in presence of two witnesses.

DARWIN H. COOK.
ERVON J. WILSON.
